US00D978922S

(12) **United States Design Patent** (10) Patent No.: **US D978,922 S**
Rajopadhye et al. (45) Date of Patent: **** Feb. 21, 2023**

(54) **HARVESTER VEHICLE, TOY AND/OR
REPLICA THEREOF**

A01D 45/021; A01D 67/00; A01D
41/1208; A01D 75/00; A01B 73/00

See application file for complete search history.

(71) Applicant: **Deere & Company**, Moline, IL (US)

(56)

References Cited

(72) Inventors: **Dhananjay Rajopadhye**, Pune (IN);
Paul M. Richardel, Polk City, IA (US);
Paul J. McCredie, Bettendorf, IA (US);
Shantanu Acharya, Pune (IN); **Vivek
Vedpathak**, Pune (IN); **Omkar

(57) **CLAIM**

The ornamental design for a harvester vehicle, toy and/or replica thereof, as shown and described.

DESCRIPTION

FIG. 1 is a perspective view of a harvester vehicle, toy and/or replica thereof according to our new design;

FIG. 2 is a first end elevational view thereof;

FIG. 3 is a second end elevational view thereof;

FIG. 4 is a first side elevational view thereof;

FIG. 5 is a second side elevational view thereof;

FIG. 6 is a first plan view thereof;

FIG. 7 is a perspective view of a harvester vehicle, toy and/or replica thereof according to another embodiment of our new design;

FIG. 8 is a first end elevational view thereof;

FIG. 9 is a second end elevational view thereof;

FIG. 10 is a first side elevational view thereof;

FIG. 11 is a second side elevational view thereof; and,

FIG. 12 is a first plan view thereof.

The above figures are depicted as grayscale images, and color forms no part of the claimed design.

The dashed lines in the figures and the relative light areas within the dashed lines show portions of the harvester vehicle, toy and/or replica thereof that form no part of the claimed design.
